UNITED STATES PATENT OFFICE.

WILLIAM H. WELLSTEED, SR., OF BRAMPTON, MICHIGAN.

ROTARY ENGINE.

1,164,897.

Specification of Letters Patent. Patented Dec. 21, 1915.

Application filed June 10, 1914. Serial No. 844,271.

To all whom it may concern:

Be it known that I, WILLIAM H. WELLSTEED, Sr., a citizen of the United States, residing at Brampton, in the county of Delta 5 and State of Michigan, have invented a new and useful Rotary Engine, of which the following is a specification.

The present invention aims to provide novel means for adjustably holding in place 10 the removable head of the stator, to provide novel means whereby the head engaging clamping ring may be held in place and adjusted, and so to construct the stator that the thrust occasioned by the clamping ring may 15 be adequately taken care of.

With the foregoing and other objects in view which will appear as the description proceeds, the invention resides in the combination and arrangement of parts and in the 20 details of construction hereinafter described and claimed, it being understood that changes in the precise embodiment of the invention herein disclosed can be made within the scope of what is claimed without 25 parting from the spirit of the invention.

In the drawings—Figure 1 is a vertical central sectional view through a rotary engine constructed according to and embodying the present invention. Fig. 2 is an end 30 elevation taken from the adjustable end of the stator, a portion of the clamping ring being broken away to show the detail structure of the head of the stator and the removable head of the rotor. Fig. 3 is a section 35 taken on line 3—3 of Fig. 1. Fig. 4 is a perspective view of one of the members of the piston.

Referring to the drawings, the numeral 1 designates the stator, which is an open ended 40 cylindrical member having an integral head 2 provided with a shaft journal opening 3. A circumferential ring 4 is disposed adjacent the outer open end of the stator, and thus provides a packing means adjacent the 45 periphery of the detachable stator head 6, which is provided with the cylindrical and tapered opening 7 which is eccentrically disposed, and the purpose of which will presently appear. The axes of the opening 7 and the journal opening 3 are alined, the purpose of which also presently appear.

Formed in the outer rim of the mouth of the stator 1 are the internal threads 8, for the reception of the external threads 9 of 55 the stator head clamping and adjusting ring 10, said ring being adapted to be rotated to

thus move the head 6 inwardly, such ring being held against rotation by means of the locking or retaining screws or bolts 11.

The rotor comprises the cylindrical member 12 and a removable disk head 22, the member 12 being provided with the diametrically disposed recess 13 which is open at three sides and is sealed at one side by means of the removable head 22. Disposed for 60 sliding movement in the recess 13 is the piston which consists of the two members 14 and 15, the detail structure of one of which is clearly illustrated in Fig. 4. Each of these members is provided with a plurality of spring receiving bores 17 for the reception of the springs 18, one to each pair of alined bores of the respective members 14 and 15. Each member is provided with the overlapping portion 19, which permit of the 65 proper guiding of the members during the rotation of the rotor and yet the necessary movements to and from each other, all as particularly shown in Figs. 1 and 3.

Formed in the flat head portion of the rotor 80 member 12 are a plurality of peripheral recesses 20, for the reception of the lugs 21 which are carried by the disk head 22 of the rotor. Thus the head 22 is properly connected to the member 12 so as to rotate therewith and yet at the same time seal the recess 13 so that the piston is properly held within the rotor. A shaft 23 is carried by the disk head 22, while the shaft 24 is carried by the member 12 and extends in an opposite direction to the shaft 23 through the stuffing 85 box 25.

The two pipes 26 and 27 are disposed relatively to the stator as shown in Fig. 3, so that the pressure fluid may be admitted 90 through either one and exhausted through the other thereof.

From the foregoing description, it is evident that any wear upon the rotor and interior of the stator may be properly taken care 100 of by means of the adjusting ring 10 and the slidably and adjustably mounted stator head 6, and that by reason of the fact that the rotor head 22 is detachably connected to the rotor member 12, access may be had to 105 the piston members of the rotor without the complete removal of the rotor from the stator chamber.

By removing the head 6, the parts of the rotor may be readily had access to and all 110 adjustments can be made from such end.

Disposed in the outer end of the respec-

tive members 14 and 15, are the packing strips 16.

Briefly considered, the rotary engine forming the subject matter of this application embodies a drum-like stator 1 provided at one end with an integral head 2, the other end of the stator 1 being open and being provided with internal threads 8. The rotor 12 is eccentrically mounted in the stator 1 and comprises a piston-slot 13 in which the piston 14-15 is mounted to move. A closure 22 is applied to one end of the rotor 12 and constitutes a piston retaining means, the closure 22 having fixed lugs 21, and the rotor 12 having openings 20 in which the lugs 21 are removably seated, thereby to permit a detachment of the closure 22 from the rotor 12 without the use of tools, but to connect the closure 22 and the rotor 12 for simultaneous rotation. The removable head 6 in the open end of the stator 1 receives the closure 22 for rotation. The retaining ring 10, having the circumferential threads 9 which coact with the threads 8 of the stator 1 abuts against the removable head 6 and constitutes a means whereby an adjustment may be effected, the screws 11 constituting a means for holding the retaining ring 10 in place, and the integral stator head 2 being well adapted to withstand the thrust created by the retaining ring. It is to be observed that the removable head 6 is provided with a crescent shaped recess 100 defining a reduced, ring engaging flange 101 and defining a closure supporting flange 102. The ring retaining flange 101 serves to decrease the friction be-

tween the ring 10 and the head 6, thus permitting a ready rotation of the ring for purposes of adjustment.

What is claimed is:

In a rotary engine, a drum-like stator provided at one end with an integral head, the other end of the stator being open and being provided with internal threads; a 45 rotor eccentrically mounted in the stator and comprising a piston slot; a piston mounted to move in the piston slot; a closure applied to one end of the rotor and constituting a piston retaining means, the 50 closure having fixed lugs and the rotor having openings in which the lugs are removably seated, thereby to permit a ready detachment of the closure from the rotor, but to connect the closure and the rotor for simultaneous rotation; a removable head in the 55 open end of the stator and receiving the closure for rotation; a retaining ring having circumferential threads coacting with the threads of the stator, the ring abutting against the removable head; means for holding the ring against rotation and in adjusted positions; the removable head having a crescent-shaped recess defining a reduced, ring engaging flange, and defining a 60 closure supporting flange.

In testimony that I claim the foregoing as my own, I have hereto affixed my signature in the presence of two witnesses.

WM. H. WELLSTED, SR.
